(**) Term: **14 Years**

CLAIM

(21) Appl. No.: **29/143,024**

The ornamental design for a light emitting aroma therapy article, as shown and described.

(22) Filed: **Jun. 6, 2001**

DESCRIPTION

(30) **Foreign Application Priority Data**

Dec. 7, 2000 (GB) 2098007

(51) LOC (7) Cl. **23-04**

(52) U.S. Cl. **D23/366**

(58) **Field of Search** D23/366, 369;
D26/5; 422/120; 239/60, 34; D7/584, 505,
565

FIG. 1 is a perspective view of the light emitting aroma therapy article embodying my new design;

FIG. 2 is a left elevational view thereof;

FIG. 3 is a right elevational view thereof;

FIG. 4 is a front elevational view thereof;

FIG. 5 is a rear elevational view thereof;

FIG. 6 is a top planar view thereof; and,

FIG. 7 is a bottom planar view thereof.
